POLYPHASE CONTROLLING DEVICE.

1,425,755.

Specification of Letters Patent. Patented Aug. 15, 1922.

Application filed May 9, 1917, Serial No. 167,827. Renewed April 7, 1921. Serial No. 459,311.

To all whom it may concern:

Be it known that EDWARD I. DEUTSCH, a citizen of the United States of America, residing at Milwaukee, in the county of Milwaukee and State of Wisconsin, has invented a certain new and useful Improvement 5 in a Polyphase Controlling Device, of which the following is a specification.

This invention relates in general to control 10 apparatus for use in connection with polyphase alternating current circuits, and has particular relation to such apparatus as is operatively responsive to any one of a plurality of abnormal operating conditions 15 in the circuit with which the apparatus is associated.

In the operations of polyphase electrical apparatus, such as motors, especially where used for driving elevators, it is very desirable to provide, in addition to the ordinary low voltage control for the apparatus, an automatic device for stopping or controlling the motor on the occurrence of such change in the phase relations of the polyphase circuit supplying the motor as might have a 25 harmful effect on the operation of the motor, such as causing its operation in the wrong direction. The simplest prior installation of this general character has involved the 30 use of two separate controlling devices, one a low-voltage controlling device, and the other a device operative in response to a change in the phase relations of the polyphase supply circuit.

In accordance with the present invention, 35 a single electromagnetically-operated controlling device is provided for use in connection with polyphase circuits, the design and construction of this device being such 40 that it is operative to produce a desired controlling effect not only in response to a low-voltage condition but also in response to a condition of phase reversal of the circuit with which the device is associated.

It is an object of the present invention 45 to provide an electromagnetically-operated device for use in connection with polyphase alternating current circuits which is of simple and improved construction and design 50 and operative on the occurrence of any one of a plurality of abnormal conditions on the polyphase circuit with which the device is associated.

It is a further object of this invention to 55 provide an improved electromagnetically-

operated controlling device for polyphase alternating current circuits embodying an electromagnet comprising relatively movable parts and energized by polyphase alternating current, and wherein effective operation 60 is in response to either low voltage or phase reversal conditions of the energizing circuit.

These and other objects are attained by this invention, the various novel features 65 of which will appear from the description and drawings, disclosing one embodiment of such invention, and will be particularly pointed out in the claims.

In the accompanying drawings:

Fig. 1 is a diagrammatic view of a polyphase alternating current system including a polyphase motor, the supply circuit for the motor being provided with controlling apparatus comprising an electromagnet em- 75 bodying features of this invention.

Fig. 2 is a diagrammatic view illustrative of the normal connections between the polyphase supply circuit and the polyphase energizing windings of the electromagnet of 80 Fig. 1.

Fig. 3 is a diagrammatic view illustrative of the current relations in the electromagnet of Fig. 1.

Figs. 4, 5 and 6 are diagrammatic views il- 85 lustrative of abnormal connections between the polyphase supply circuit and energizing coils of the electromagnet of Fig. 1.

Fig. 7 is a diagrammatic view illustrative of the normal flux relations in the core of 90 the electromagnetic device of Fig. 1, considered especially as to a point at the center of the surface of engagement between that end of the pivoted armature which is remote from the axis of the armature 95 and the co-operative polar portion of the relatively stationary core.

Fig. 8 is a diagrammatic showing of the normal flux paths through the electromagnetic device of Fig. 1.

As shown in Fig. 1 of the accompanying drawings, a polyphase circuit *a*, *b*, *c* supplies the branch circuit *B* of a translating device, such as the motor *M* having leads *x*, *y*, *z*, connected to the conductors *a*, *b*, *c*, 105 respectively, when the connections between the motor and the supply circuit are normal. The circuit *B* may be provided with fuses *F*, as indicated. A controlling device *C* of any ordinary or suitable design is 110

located in the branch circuit at some point between the supply circuit *a*, *b*, *c*, and the motor leads *x*, *y*, *z*. In the embodiment illustrated, the controller C is in the form 5 of a switch having a triple-pole circuit-closing element S mounted on an operating rod 12. This circuit controller is normally biased to circuit-open position by a suitable spring 13 acting on links 14 and 15 which 10 are pivotally connected together, the link 14 being connected to the rod 12 and the link 15 being connected to a fixed pivot, as indicated at 16, and operable by a handle 17. The tendency of the spring 13 is to 15 force upward the pivotal connection between the links 14 and 15 and thus draw the switch S to the left to open position. Under normal operating conditions of the motor M, the switch S is retained in closed 20 position by the engagement of a projection 18 on the link 15 with a shoulder at the end of the arm 19 of a latch L pivotally mounted on a fixed pivot, as indicated at 21. This latch is retained in locking position to hold 25 the switch S closed, by a spring 23 fixed at one end and connected at the other end to the arm 19 of the latch. Suitable stops may be provided for limiting the movement of the latch to that desired. The 30 latch may be provided with an arm 24 carrying a finger piece at its end whereby the latch may be manually released, if such operation is desirable.

While the controller illustrated is of simple form, being an ordinary switch or circuit-breaker, as indicated, it will be obvious that any suitable control means may be substituted for that shown. This controller may be in the form of the ordinary starting compensator or potential starter used 40 with polyphase motors, and the latch may be effective to hold the starter in running position or to release the same from such position, under which conditions a spring 45 or other means may be effective to return the starter to "off" position.

It has been customary to provide an auxiliary device for accomplishing the automatic release of the holding latch L on the 50 occurrence of predetermined abnormal circuit conditions. In the majority of cases a low-voltage responsive magnet is a necessary feature of the controller; also, in many instances, it is required that the controller be automatically released on phase 55 reversal of the circuit.

The present invention includes the provision of a unitary electromagnetically-actuated device which is effective to trip the 60 latch L on the occurrence of either low voltage or phase reversal of the circuit. This electromagnetic device E comprises a core 25, preferably stationary, and a pivoted armature 26, the latter being preferably of 65 considerable weight and pivoted at a fixed

point located to one side of a vertical line through the center of gravity of the armature when in attracted position, as indicated at 27. As will be apparent, when the magnetic circuit of the magnet is sufficiently energized, the armature is retained in attracted position, as indicated; and, under conditions of insufficient energization, the armature is permitted to drop due to the action of gravity. Mounted on the core and 70 arranged side by side thereon polyphase energizing windings 28, 29 are shown, the terminal 31 of the winding 28 being connected to the lead *x* of the motor M, the lead 32 of the winding 28 and the lead 34 80 of the winding 29 being electrically connected together and to the lead *y* of the motor, and the lead 35 of the winding 29 being connected to the lead *z* of the motor. As will be apparent from the connections 85 indicated, these energizing coils 28, 29 are connected in open delta to the supply circuit of the motor, having a permanent connection with the leads *x*, *y*, *z*. It is also apparent that the coils 28, 29 may be oppositely wound, the direction of winding of coil 28 being opposite to that of coil 29, so that if a current were passed through coils 28 and 29 in series, the magnetic effects produced in the core would be substantially 90 equal and opposite.

Of course, the utility and ordinary operation of a low-voltage responsive device customarily used in connection with controlling apparatus of the character described above 100 is readily apparent. It often happens, however, especially after any repairs to the motor, or other translating device, or the overhauling of the controller or the connections to the supply circuit, or even after replacing 105 a couple of fuses in the branch circuit, that a pair of circuit connections are accidentally interchanged. This accident has the effect of reversing one phase of the circuit and, in the case of a motor, causing operation thereof in a reverse direction. Such an accident, especially where the motor is used for elevator service, may have disastrous consequences. Hence, the necessity of preventing operation of the translating device 110 after any such phase reversal.

It will be apparent that when energized from the three-phase supply circuit *a*, *b*, *c*, through the branch circuit B, the energizing windings 28, 29, connected in open-delta, 120 as indicated in Figs. 1 and 2, are effective to produce a three-phase flux in the core 25 of the electromagnet. In accordance with this invention, the construction and design of the core, armature and energizing windings 125 are such that three-phase magnetic fluxes are produced in the magnet core. One of these fluxes is due to current in coil 28 across phase *a*—*b*, another is due to current in coil 29 across phase *b*—*c* and 130

the third flux is due to current in the coils 28 and 29 in series across phase $a-c$, this latter current being equivalent to a resultant of the other two currents and displaced 5 180 degrees from normal position so as to be spaced 120 degrees from each of the other two currents. That three such currents are present in an arrangement of open-delta connected transformer windings will 10 be readily apparent. Were it not for the fact that one coil is reversed with respect to the other, these three currents would produce in the core three fluxes 120 degrees apart; however, with one coil reversed, the flux due thereto is reversed. Thus, there are present in the core three 15 fluxes spaced apart 60 degrees.

In any case, the resultant flux is effective 20 to hold the armature 26 in attracted position when the voltage on the circuit to which the windings are connected is normal, or above a certain minimum value. When the voltage applied to the terminals of the energizing windings 28, 29, or the motor terminals 25 to which the energizing windings are connected, is below that minimum value, the resultant flux in the magnet is ineffective 30 to hold the armature 26 in position; and this is also the case when, even through 35 normal voltage is applied to the terminals of the energizing coils, there is a reversal of one phase of the current supplied to the energizing winding. Under either of these conditions, the armature 26 is released and, 40 acting as a hammer, forcibly engages an anvil-like extension 37 on the arm 24 of the latch L, causing such actuation of the latter as permits the controlling device to move to circuit-open position.

Fig. 2 is a diagrammatic showing of the 45 normal connections between the supply circuit a, b, c and the energizing windings 28, 29, that is, those present when the motor M is operating in the desired direction. With 50 the connections indicated here, there is supplied to the energizing windings 28, 29 of the electromagnet three-phase currents 120 degrees apart and having a maximum value proportionate to the voltage on the circuit. The relations between these currents is indicated in Fig. 3, where $a-b$ represents the 55 current in coil 29 due to the potential drop across conductors a and b , $b-c$ represents the current in coil 29 due to the potential drop across conductors b and c , and $a-c$ represents the current in the coils 28 and 29 due to the potential drop across conductors a and c . However, these lines $a-b$, $a-c$ and $b-c$ of Fig. 3 do not represent current magnitude, but rather only relative angular directions of the currents at one instant, the actual 60 instantaneous values of the currents produced thereby being proportionate to $\sin \theta, \sin (0+120^\circ)$ and $\sin (0-120^\circ)$, respectively, where θ may be any value between

0 and 360° . Likewise, the values of the fluxes due to these currents will be in the same proportion as the currents producing the fluxes; and the resultant flux at any point of the magnet core may be obtained 70 by adding the individual fluxes vectorially.

Fig. 7 may be considered as a diagrammatic showing of the flux conditions present at a certain point in the core of the electromagnet, this point being designated "X" 75 in Fig. 8, and may be considered as practically any point in the plane of engagement of the remote polar portion of the armature and the co-operative polar portion of the core. Obviously, the flux and the consequent magnetic pull at this point of the electromagnet is most effective in holding 80 the armature in attracted position.

$B-C$ may be considered as flux due to current in the phase $b-c$, $A-B$ as flux due 85 to current in the phase $a-b$, this latter flux being in the position indicated, instead of a position 180 degrees therefrom, because of the fact that the direction of the current flow is reversed in the winding 28, and $A-C$ 90 as flux produced by current in the coils 28 and 29 due to current in the phase $a-c$, this latter current being due to the transformer effect of the coils 28 and 29 of the electromagnet. From a consideration of 95 Fig. 8, showing the normal flux paths in the electromagnetic device, it will be apparent that the flux $A-C$ due to current of the phase $a-c$ in the winding 28 has no appreciable effect at the point "X" of the 100 electromagnet. For facility in considering the matter, the flux due to current of the phase $a-c$ in the coil 28, has its path designated $(A-C)^{28}$ and the flux due to current of the phase $A-C$ in the winding 29 has 105 its path designated $(A-C)^{29}$. It will be apparent that the normal paths of the fluxes due to current of the phase $a-b$ in the winding 28, designated as $A-B$, and flux due to current of the phase $b-c$ in the winding 29, designated as $B-C$, is through the 110 entire body portion of the core 25 and the two polar portions of the armature 26. Considering the two fluxes $(A-C)^{28}$ and $(A-C)^{29}$, due to current of the phase $a-c$, 115 it must be remembered that, while they are due to current of the phase $a-c$, nevertheless, due to the fact that the coil 28 is wound oppositely to the coil 29 and laterally displaced therefrom, these two windings produce fluxes of similar polarity at a point in the core between the adjacent ends of the coils 28 and 29, thus causing the formation of separate flux paths. The flux $(A-C)^{29}$ 120 has its normal path across the air gap containing the point X, and this flux is active to produce an effective pull upon the armature; while the flux $(A-C)^{28}$ can produce no appreciable effect upon the armature.

The effective pull at the point X is the 130

resultant of the three fluxes A—B, B—C, and (A—C)²⁹, these three fluxes being 60 degrees apart, as indicated in Fig. 7. Under normal conditions with phase connections as indicated in Fig. 2, the armature 26 is held in attracted position as long as the voltage on the circuit remains normal, or above a certain minimum value, the pull on the armature 26 being proportionate to the potential across the terminals of the windings and having a definite effective value for any definite voltage. It will be apparent that when this voltage is reduced below a certain minimum value, the resultant flux is insufficient to hold the armature 26 in attracted position, and the latter drops away and actuates the latch L, causing the controller C to move to circuit-open position.

If, for any reason, as through accident on the part of a repair man, the connections between a pair of the conductors of the circuit a, b, c and the leads x, y, z , and consequently the leads of the energizing coils 28, 29 are reversed, the motor tends to operate in a reverse direction, and there is a change in the normal current or flux relations in the electromagnet E.

It may be assumed that the circuit connections from the conductors a and b are reversed, as indicated diagrammatically in Fig. 4. The result of such reversal of the circuit connections on the flux produced in the core 25 of the magnet, say at the point X, by the energizing windings 28, 29 may be noted from the diagrammatic showing of Fig. 8. It will be apparent that the flux produced by the current due to the potential drop across conductors a and b becomes flux B—A, and is, therefore, reversed and shifted 180°. Flux B—C becomes flux A—C and is, therefore, shifted 120°, and flux A—C becomes flux B—C and is therefore shifted 120°. As before, the flux (A—C)²⁸ has no effect at the point X at the air gap. The result obtained when one phase is reversed is, therefore, that the flux due to this phase is shifted 180°, and the flux due to each of the other two phases is shifted 120°, that is, each of the two latter fluxes merely change positions. If all three fluxes are considered to have the same maximum value, the net result obtained at the point X, so far as external influence is concerned, is that one flux is shifted 180°, for the two remaining fluxes simply change positions, giving a resultant effective flux at the air gap of substantially zero.

While the diagrammatic showing of Fig. 7 assumes that the flux A—B is reversed from its normal position with respect to the flux B—C, nevertheless, it is just as correct to assume that the flux B—C is reversed from its normal position with respect to the flux A—B, and a flux diagram wherein both flux-

es B—C and A—B are positioned 180 degrees from that shown in Fig. 7 is representative of the normal flux condition at the point X of the electromagnet. With this assumption, it will be apparent that there are still three fluxes 60 degrees apart at the point X of the electromagnet.

Now assume that the connections between the conductors of the supply circuit a, b, c and the terminals of the motor and, consequently, the energizing windings 28, 29 of the electromagnet, are reversed in the manner indicated in Fig. 5, wherein the connections from the conductors b and c are reversed. Then, considering the diagram of Fig. 7, it will be apparent that flux B—C is reversed from the normal condition assumed and, therefore, reversed or shifted 180°. As described before, the other two fluxes, A—B and (A—C)²⁸, are shifted 120°. As in the case of the phase reversal indicated in Fig. 4, one flux is shifted 180° and the other two fluxes merely change positions, giving a resultant effective flux at the air gap of substantially zero.

If the connections between the conductors of the supply circuit a, b, c and the terminals of the motor and, consequently, the windings 28, 29 are such as are indicated in Fig. 6, wherein the connections from the conductors a and c are reversed, then, considering the flux diagram of Fig. 7, it will be seen that the portion of the flux A—C indicated in Fig. 8 as (A—C)²⁹, the latter being the only portion of the flux A—C that is effective at the air gap, is reversed or shifted 180°, and the resultant effect is the same as when the leads b and c were reversed, as above described. As before, the net result of the change in circuit connections indicated in Fig. 6 is that the flux due to one phase is reversed or shifted 180°, and the fluxes due to the other two phases may be considered as merely changing positions, giving a resultant effective flux and pull at the air gap of minimum value.

It will be apparent that with the connections between any pair of conductors of the supply circuit and the motor terminals, or the terminals of the windings 28, 29 reversed, the flux produced in the core 25 of the electromagnet, that is, at the air gap between the core proper and the armature, becomes of minimum value, and the armature is thus permitted to drop away.

As stated above, the construction and design of the electromagnetic device E, as to electrical and magnetic features, is such as to utilize this difference between the resultant fluxes occurring when the connections between the energizing windings 28, 29 and the supply circuit are normal and when one pair of connections are reversed. As disclosed, the armature 26 is held in attracted position while the voltage on the motor

windings and the windings 28, 29, is normal, or above a certain minimum value, and the armature is released, causing actuation of the controller C to circuit-open position, 5 when the voltage drops below a certain minimum value or there is a reversal of one of the phases of the polyphase energy supplied to the motor and the magnet windings 28, 29. It will be apparent that there is provided a 10 single unitary device which not only acts as a low-voltage relay or operating device, but is also capable of securing the desired operation on the occurrence of reversal of any phase of the circuit. It will be observed 15 that one of the features which makes for extreme simplicity in the described device for attaining the foregoing results is that a fixed effective flux-path is utilized as distinguished from certain prior art devices depending for operation on the rotation or shifting of a magnetic flux thus involving a non-fixed path. In this fixed flux-path a substantially uni-directional resultant of the polyphase fluxes is produced 20 by a vectorial addition thereof, as has already been pointed out.

While the electromagnetic operating device or relay is shown and described as actuating a latch to permit or cause the return 30 of the controlling device to "off" position, this is to be considered merely as illustrative of one use, for it will be obvious that the device may have other uses, such, for instance, as causing the completion or rupture of a 35 relay tripping circuit for a circuit-breaker or controller, or, in fact, to accomplish any desired operation.

While the above explanation as to the electromagnetic effects present in the operation 40 of the device may not be the most nearly correct one, nevertheless, it has been demonstrated that a device constructed in accordance with this invention is possessed of novel and desirable characteristics.

45 It should be understood that it is not desired that the invention claimed be limited to the exact details of construction shown and described for obvious modifications will occur to a person skilled in the art.

50 It is claimed and desired to secure by Letters Patent:

55 1. In a controlling device for polyphase electric circuits, a controlling element, and means for causing actuation of said controlling element when the phase relations are different than a predetermined relation, said means including an energizing means whereby an appreciable effective normal flux is produced having windings for producing 60 a vectorial addition in substantially a single direction of polyphase effects proportional to the line voltages of said polyphase circuit.

65 2. In a controlling device for polyphase electric circuits a movable controlling ele-

ment, and means for causing actuation of said controlling element when the phase relations are different than a predetermined relation, or when the voltage drops to a predetermined value, said means including 70 energizing means producing a flux substantially proportional to a substantially uni-directional resultant of the polyphase potentials.

3. In a controlling device for polyphase electric circuits a movable controlling element, and means for causing actuation of said controlling element when the phase relations are different than a predetermined relation, or when the voltage drops to a 80 predetermined value, said means including movable and stationary core elements and energizing means for said core elements producing a flux substantially proportional to a uni-directional resultant of the polyphase 35 potentials.

4. In a controlling device for polyphase electric circuits, controlling means, means for rendering said controlling means effective to exercise its controlling function in 90 response to a relation of phases other than a predetermined relation of phases or in response to a drop in voltage to a predetermined value, said means including energizing means producing a predetermined 95 effective quantity of flux with a predetermined relation of phases and a less quantity with another relation of phases.

5. In a controlling device for polyphase electric circuits, controlling means, means for rendering said controlling means effective to exercise its controlling function, said means including energizing means producing a predetermined effective quantity of flux with a predetermined normal relation of 100 phases and a less quantity with another relation of phases.

6. In a controlling device for polyphase electric circuits, a controlling element, and means for causing actuation of said controlling element when the phase relations are different than a predetermined relation, or when the voltage drops below a predetermined value or is unbalanced to a predetermined extent, said means including energizing means having a fixed flux path. 110

7. In a controlling device for polyphase electric circuits, a controlling element, and means for causing actuation of said controlling element when the phase relations are different than a predetermined relation, said means including energizing means having a fixed flux path and an appreciable constant effective normal flux through said path. 120

8. In a controlling device for polyphase electric circuits, a controlling element, and means for causing actuation of said controlling element, said means including a magnetic circuit having a stationary portion, a movable member for coacting with said sta- 125 130

tionary portion, said movable member being normally held in a raised position by said stationary portion and capable of delivering a hammer blow when released, and means for energizing said stationary portion including a plurality of windings each adapted to be connected across a different phase of said polyphase circuit.

9. In a controlling device for polyphase electric circuits, a controlling element, and means for causing actuation of said controlling element, said means including a magnetic circuit having a stationary portion, a movable member for reacting with said stationary portion, said movable member being normally held in a raised position by said stationary portion and capable of delivering a hammer blow when released, and means for energizing said stationary portion including a plurality of windings each adapted to be traversed by currents of different phase.

10. In combination with a polyphase circuit, a circuit-controlling device for said circuit, and means for causing actuation of said circuit-controlling device on the occurrence of low voltage on said circuit or the reversal of one of the phases of said circuit, said operating means comprising an electromagnet having a core and polyphase energizing windings therefor, and an armature biased away from said core and movable into engagement with a polar portion thereof, said windings being effective to energize said core and armature to an extent sufficient to hold said armature in attracted position without appreciably exceeding saturation of the magnetic circuit of said electromagnet during conditions of normal voltage and phase relation and being ineffective to hold said armature in attracted position when the voltage is below a certain value or one of the phases of said circuit is reversed.

45 11. In combination, a controlling element and an electromagnetically-operated device for causing actuation of said controlling element and comprising an armature cooperative with a polar portion of said core and biased away from attracted position relative to said polar portion of the core, a plurality of winding sections energized by currents of different phase associated with said core whereby a resultant flux is produced in said core which is dependent in value upon the ampere turns of said winding and the relation between the phases of current supplied to said winding sections, said armature being held in attracted position relatively to 55 said core against movement due to its bias while the voltage and phase relations of the energizing circuit are normal and movable away from said core on the occurrence of low voltage or the reversal of one phase of

said circuit to cause actuation of said controlling element.

12. In a controlling apparatus for polyphase electric circuits, an electromagnet comprising a core and a movable armature cooperative therewith, and windings energized with currents of different phase, the resultant flux in said core due to said windings being sufficient to retain said armature in inoperative position under conditions of normal voltage and phase relations and being insufficient to retain said armature in inoperative position when the voltage drops below a certain value or one phase of the circuit is reversed, and a circuit-controlling device actuated by said armature on movement thereof from said inoperative position.

13. In a controlling device for polyphase circuits, a controlling element, and means for causing actuation of said controlling element when the phase relations are other than of a predetermined character, said actuating means including energizing means comprising a normally energized core and two energizing coils therefor connected in open-delta to the circuit to be controlled and disposed side by side on said core.

14. In a controlling device for polyphase circuits, a controlling element, and means for causing actuation of said controlling element when the phase relations are other than of a predetermined character or when the voltage drops below a predetermined value, said actuating means including an energizing means comprising a core, and two energizing coils therefor connected in open-delta to the circuit to be controlled and disposed side by side on said core.

15. In a controlling device for polyphase circuits, a controlling element, and means for causing actuation of said controlling element when the phase relations are other than of a predetermined character or when the voltage drops below a predetermined value or is unbalanced to a predetermined extent, said actuating means including an energizing means comprising a core, and two energizing coils therefore connected in open-delta to the circuit to be controlled and disposed side by side on said core.

16. In a controlling device for polyphase circuits, a controlling element, and means for causing actuation of said controlling element when the phase relations are other than of a predetermined character, said means including an energizing means comprising a core, and two energizing coils therefor differentially connected in open-delta to the circuit to be controlled and disposed side by side on said core.

17. In a controlling device for polyphase circuits, a controlling element, and means for causing actuation of said controlling element when the phase relations are other

than of a predetermined character or when the voltage drops below a predetermined value, said means including an energizing means comprising a core, and two energizing coils therefor differentially connected in open-delta to the circuit to be controlled and disposed side by side on said core.

18. In a controlling device for polyphase circuits, a controlling element, and means for causing actuation of said controlling element when the phase relations are other than of a predetermined character or when the voltage drops below a predetermined value or is unbalanced to a predetermined extent, said means including an energizing means comprising a core, and two energizing coils therefor differentially connected in open-delta to the circuit to be controlled and disposed side by side on said core.

20 19. In a controlling device for polyphase electric circuits, a controlling element, and

means causing actuation of said controlling element when the phase relations are different than a predetermined relation, said means including an energizing means 25 whereby an appreciable effective normal flux is produced having windings for producing vectorial addition in substantially a single direction of polyphase effects produced by said polyphase circuit. 30

20. In a controlling device for polyphase electric circuits, a controlling element, and means for causing actuation of said controlling element when the phase relations are different than a predetermined relation, 35 or when the voltage drops to a predetermined value said means including an energizing means having windings connected to said polyphase circuit.

In testimony whereof, the signature of 40 the inventor is affixed hereto.

EDWARD I. DEUTSCH.

Certificate of Correction.

It is hereby certified that in Letters Patent No. 1,425,755, granted August 15, 1922, upon the application of Edward I. Deutsch, of Milwaukee, Wisconsin, for an improvement in "Polyphase Controlling Devices," an error appears in the printed specification requiring correction as follows: Page 5, line 123, claim 7, strike out the word "constant"; and that the said Letters Patent should be read with this correction therein that the same may conform to the record of the case in the Patent Office.

Signed and sealed this 19th day of September, A. D., 1922.

[**SEAL.**]

WM. A. KINNAN,

Acting Commissioner of Patents.
